Primary Examiner — Eric Goodman*Assistant Examiner* — Brett Miller(74) Attorney, Agent, or Firm — Griffiths & Seaton PLLC; JoAnn M. Seaton(57) CLAIM

The ornamental design for a bowl with clip, as shown and described.

DESCRIPTION

FIG. 1 is a front, perspective view of a bowl with clip showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The feature shown in broken lines is a portion of the bowl with clip forming no part of the claimed design.
